CLAIM

I claim the ornamental design for a musical instrument stand,
as shown and described.

DESCRIPTION

FIG. 1 is a front and left side perspective view of a musical instrument stand in a closed or retracted state showing my new design;

FIG. 2 is a front and top view of the embodiment depicted in FIG. 1;

FIG. 3 is a rear and top view of the embodiment depicted in FIG. 1;

FIG. 4 is a front and bottom view of the embodiment depicted in FIG. 1;

FIG. 5 is a rear and bottom view of the embodiment depicted in FIG. 1;

FIG. 6 is a right side view of the embodiment depicted in FIG. 1;

FIG. 7 is a left side view of the embodiment depicted in FIG. 1;

FIG. 8 is a front and right side perspective view of a musical instrument stand showing an embodiment in an open position;

FIG. 9 is a front view of the embodiment depicted in FIG. 8;

FIG. 10 is a rear view of the embodiment depicted in FIG. 8;

FIG. 11 is a front view viewed along an axis of an extended rear leg of the embodiment depicted in FIG. 8;

FIG. 12 is a rear view viewed along the axis of the extended rear leg of the embodiment depicted in FIG. 8;

FIG. 13 is a left side view of the embodiment depicted in FIG. 8;

FIG. 14 is a right side view of the embodiment depicted in FIG. 8;

FIG. 15 is a top view of the embodiment depicted in FIG. 8; and,

FIG. 16 is a bottom view of the embodiment depicted in FIG. 8.

Applicants expressly reserve the right to modify any of FIGS. 1–16 to show, in line drawing format, any feature depicted in solid lines in dashed lines. Any surfaces of the design not shown, including interior surfaces, and the subject matter of any portions subsequently shown in dashed lines form no part of the claimed invention.
